UNITED STATES PATENT OFFICE

1,987,137

SYRINGE

James Warren Walters, Tulsa, Okla.

Application April 16, 1934, Serial No. 720,866

1 Claim. (Cl. 128—239)

This invention relates to syringes especially adapted for veterinary use.

The main object of the invention is to provide a device of this kind having means to penetrate the part of the anatomy of the animal desired to be treated, and vacuum means to properly position the wall of the anatomy so the interior thereof can be cleansed in the most efficient manner.

10 Another object of the invention is to provide a rectal front end in the shape of an arrow head to penetrate the anatomy of the animal, a vacuum cup adapted to distend the wall thereof, and means to pump a fluid in the interior of the anatomy to properly cleanse same.

15 Other objects of the invention will appear as the disclosure progresses. The drawing is intended to merely indicate a possible embodiment of the invention. It is obvious that the actual needs of manufacture may necessitate certain 20 mechanical changes. It is therefore not intended to limit the invention to the embodiment illustrated but rather to define such limits in the appended claim.

25 For a more general understanding of the invention attention is called to the drawing. In the drawing like reference characters denote like parts throughout the specification.

30 In the drawing

Figure 1 is an outside view of the syringe. Figure 2 is a longitudinal section thereof and Figure 3 is a cross section on line 3—3 of Figure 2.

35 Referring now to the drawing in detail, numeral 1 designates the cup to create a vacuum, 2 the hollow stem and 3 the rectal front end in the shape of an arrow head. The rear wall 4 of the cup is provided with a hole 5 to allow the stem to pass through. Pivotally connected to the rear 40 of the wall is a catch 6 for keeping the position between the stem and cup adjusted. The lower point of the catch is adapted to engage with the threaded portion 7 of the stem and near the top of the catch is a compression spring 8 partly embedded in the wall 4 of the cup for normally urging the upper part of the catch outwardly. The outward portion of the stem is provided with a knob 9 for conveniently gripping or holding the device. Attached to the extreme end of the 45 stem is a hose 10.

50 Threadedly engaging the portion of the stem which is housed in the interior of the cup is a leather piston 11 adapted to create a vacuum in the cup. The forward end of the cup is provided

with a bead 12. A part of the function of this bead is to act as a stop for the forward movement of the piston so that when the piston is moved forward it will come in contact with said bead, and the piston being made of soft leather will stop without a jar.

The interior of the element 3 is provided with a longitudinal bore 13 which matches up with the bore of the stem. The bore 13 is enlarged at the front as at 14 and in the interior thereof is a ball valve 15. Screwed into the tip of the element 3 is a short nipple 16 having a bore 17 on line with the bore 13. Numeral 18 designates a pin passing through the nipple and adapted to prevent the ball valve from leaving its housing.

The operation of the device is as follows: The spear headed rectal nozzle 3 is moved forward of the cup 1 as indicated in Figure 1 and inserted in the cavity of the animal to be treated so that the fleshy part of the anus may slip over the 20 enlargement of the rectal nozzle and into the front end of the vacuum. The piston is then moved to the right in the position shown in Figure 2. This will create a vacuum within the cup and will draw in the fleshy part of the anus between the rectal nozzle and the bead 12 making a 25 comparatively leak-proof joint. The next step is to pump a medicinal liquid by means of a pump (not shown) through the hose 10, through the rectal nozzle and thence into the interior of the 30 anatomy of the animal. The ball valve will prevent the medicinal liquid from flowing back into the hose and the catch will prevent the piston from moving and thus sustain the vacuum.

35 It will thus be seen that I have provided a simple and efficient device to treat an ailing animal in the most modern and scientific manner.

Having described my invention, I claim

40 In a device of the class described, a cup, the front end of said cup being internally beaded, a piston in said cup for creating a partial vacuum, a hollow stem, said piston mounted on said hollow stem, said stem passing an aperture in the rear wall of said cup, a hollow tapered enlargement 45 surrounding the front end of said stem, a ball valve near the tip of said enlargement, a catch pivoted to the said rear wall of said cup and adapted to engage a rack on the said stem to adjust the relative position between said enlargement and said cup, and a knob near the rear of 50 said stem for conveniently holding and manipulating said stem.

JAMES WARREN WALTERS.
